RADIO APPARATUS

Eugene F. McDonald, Jr., Chicago, Ill.

Application June 26, 1939, Serial No. 281,297

9 Claims. (Cl. 250—14)

This invention relates to radio apparatus, and more particularly to antenna structure particularly adapted for employment with portable radio receiving sets.

Portable radio receiving sets are frequently provided with loop antennas built into the set, usually taking the form of the rear panel of the casing of the set. The desired location of the set is not always the best position for the antenna and this is particularly true when attempts are made to use portable radio receiving sets within metal shielding structures such as Pullman cars, airplanes, boats, etc. It has heretofore been found impossible to secure satisfactory reception with a portable receiving set when positioned in such shielding structures. In accordance with the present invention, an antenna which is removable from the set but connected thereto by a flexible connection is provided with means for quickly attachably and detachably securing the same to a surface for supporting the same in a plane parallel to the surface or in any angular relationship with respect to the surface. The antenna may thus be adjustably supported adjacent any opening in the shielding structure so as to enhance or render radio reception possible.

An object of the present invention is to provide a device for enhancing the reception of signals by a radio receiving set positioned within a shielding structure.

A further object of the invention is to provide a movable radio antenna which may be quickly attachably and detachably secured to a surface and adjusted to any desired angle with respect to the surface.

Another object of the invention is to provide a radio receiving set with a removable antenna which may be quickly attachably and detachably secured to a surface in any one of a plurality of positions either parallel to the surface or at any angle thereto.

Other objects and advantages of the invention will appear in the following description of preferred embodiments thereof shown in the attached drawings, of which:

Figure 1 is a perspective view of a portable radio receiving set and antenna as employed in a railroad car;

Figure 2 is a side elevation of a radio receiving set in accordance with the present invention with portions thereof broken away;

Figure 3 is an elevation of an antenna in accordance with the present invention with portions broken away;

Figure 4 is a plan view of the antenna of Figure 3;

Figure 5 is a view similar to Figure 4 showing the antenna at an angle to the surface to which it is secured;

Figure 6 is an elevation of a modified form of antenna;

Figure 7 is a fragmentary cross section taken on line 7—7 of Figure 6;

Figure 8 is a plan view of the joint between the antenna of Figure 7 and its supporting means;

Figure 9 is an elevation of the joint shown in Figure 8;

Figure 10 is an elevation of a still further modified antenna structure; and

Figure 11 is a fragmentary section taken on the line 11—11 of Figure 10.

Referring to the drawings and more particularly to Figure 1, 10 indicates a portable radio receiving set shown as positioned on a table 11 in 20 a railroad car. An antenna structure 12 connected to the receiver 10 through a flexible connection 13 is shown as secured to the surface of the glass 14 of a window of the car by means of suction cups 15 and 16. The antenna structure 12 ordinarily forms the rear portion of the casing of the set 10, as shown in Figure 2. Such antenna structure may include a panel member 17, a panel member 18 and a loop antenna formed of conductors 19, positioned between the panels 17 and 18. The panel 18 may be secured to the panel 17 in any desired manner, such as the bolts 20 shown in Figure 3.

Referring again to Figure 2, the antenna structure may have a member 21 secured to the lower part of the panel member 17 and having a portion engaging a groove 22 in a member 23 secured to the base member 24 of the casing of the set 10. The upper portion of the panel member 17 may have a projection 25 which is adapted to enter into and be retained by a spring clip 26 carried by the upper casing member 27 of the set 10. The members 21 and 23 cooperate with the projection 25 and spring clip 26 to retain the antenna structure in position in the casing of the set 10, although any other suitable means may be employed for securing the antenna structure to the casing of the set 10.

The flexible connector member 13 preferably comprises a flat fabric tube in which are sewed 50 conductors 28, as more clearly shown in Figure 3. As shown in Figure 2, the flexible connector may be folded within a compartment of the set formed by the antenna structure 12 and a partition panel 29. The flexible connecting member 13 connects 55

the antenna to the set in all positions thereof so that the antenna is capable of receiving signal energy and delivering the same to the set either when positioned in the set as shown in Figure 2 or when supported externally of the set as shown in Figure 1. Thus the receiving set is operative under ordinary conditions with the antenna positioned therein, but the antenna may be removed and supported upon a surface apart from the set under abnormal conditions in order to enhance radio reception.

As shown in Figures 3-5, inclusive, a suitable arrangement for enabling the antenna to be adjustably supported on a surface apart from the set is to hinge the vacuum cups 15 to one edge of the panel member 18 by means of hinges 30 and secure the vacuum cup 16 to the panel 18 by pivoting the same to a link member 32 which is pivoted to a bracket 33 secured to the panel 18 adjacent the center thereof. As shown in Figure 4, the antenna may be positioned parallel to the surface of the glass 14 or other surface, and as shown in Figure 5 the antenna structure 34 may be positioned at any desired angle to the plane of the surface.

A modified structure providing for universal adjustment of an antenna structure 34 is shown in Figures 6 to 9, inclusive. In the structure shown in these figures, an auxiliary supporting member 35 carrying vacuum cups 36 is attached to one corner of the panel member 17 by means of a ball and socket joint 38. A suitable ball and socket joint 38 is shown more clearly in Figures 7 to 9 and may include a pair of formed sheet metal members 39 and 40 secured in any desired manner to the panel member 17, for example, by the screws 41. The members 39 and 40 may have upstanding flanges 42 and 43, respectively, having spherical portions 44 formed intermediate their ends to provide a socket to receive a ball member 45 forming a part of a plate member 46, secured to the supporting member 35 carrying the vacuum cups 36. The upstanding flange 42 of the member 39 may have its end portions 47 reversably bent and threaded to receive screws 48 serving to clamp the upstanding flange 43 of the member 40 to the upstanding flange 42 of the member 39 in order to clamp the member 45 in the socket formed between the flanges 42 and 43 so that the spherical portions thereof frictionally engage the ball member to form a universal friction hinge. It will be apparent that the supporting member 35 may be quickly attached to a supporting surface in any desired position and that the antenna structure 34 may then be adjusted to any desired angular position with respect to the surface. The engagement of the formed portions 44 of the flanges 42 and 43 with the ball member 45 may be made sufficiently tight that the antenna structure is rigidly held in adjusted position but can be manually moved to any other adjusted position.

A still further modified antenna structure 46 is shown in Figures 10 and 11. In the structures shown in these figures, a single vacuum cup 48 is secured to one leaf 50 of a friction hinge 58 and the other leaf 51 of the hinge 58 is secured to the panel member 18 of the antenna structure 46. A spider member 52 may be secured to the leaf 50 of the friction hinge 58 concentric with the vacuum cup 48. The spring spider member 52 has a plurality of outwardly extending spring fingers 53 which extend into the plane of the surface 54, to which the vacuum cup 48 is

adapted to be secured, and prevent stresses parallel to the surface from detaching the vacuum cup 48.

The present invention has major utility with portable radio receiving sets and renders the same efficiently operable even when positioned within shielding structures. Although positioning the antenna structure in the center portion of an opening such as the window 14 of Figure 1 would reasonably appear to provide the best location for reception within a shielding structure, it has been found that most efficient reception of signal energy is usually obtained when the antenna structure is positioned adjacent the edge of the opening and in most cases positioning the antenna structure in the corner of an opening gives most efficient reception. It has also been found that for stations in different directions from the receiving antenna, different positions adjacent the opening and different angular relationship with respect to the plane of the opening are required for optimum reception. The structure of the present invention provides for quickly positioning and supporting the antenna in the position of best reception.

While the invention has been particularly described with reference to a portable radio receiving set having a single antenna capable of being positioned within to form part of the set and also capable of being removed therefrom and quickly attached or detached from a supporting surface, it is apparent that the antenna structure of the present invention may be employed for other types of antennas and may form an auxiliary antenna capable of being optionally substituted for the antenna normally carried by the set.

Although I have specifically disclosed preferred embodiments of the invention, it is understood that the details thereof may be varied within the scope of the following claims.

I claim:

1. In a radio receiving apparatus comprising a radio receiving set operative under normal conditions to receive radio signals, the improvement which comprises, means for enhancing reception of said signals under abnormal conditions when said set is positioned within a shielding structure having an opening therein, said means comprising an antenna structure including conductors attached to a panel, an elongated flexible member electrically connecting said conductors to said set, and means provided on said panel forming a unitary structure therewith and constructed and arranged for quickly attachably and detachably securing the same to a surface in any one of a plurality of positions relative to said opening and apart from said set, said last named means including means for securing said antenna to said surface either parallel to said surface or at an angle thereto.

2. In a radio receiving set provided with an antenna carried by said set and operative under normal conditions to receive radio signals, the improvement which comprises means for enhancing reception of said signals under abnormal conditions when said set is positioned within a shielding structure having an opening therein, said means comprising an elongated flexible member electrically connecting said antenna to said set and means provided on said antenna constructed and arranged for quickly attachably and detachably securing the same to a surface in any one of a plurality of positions relative to said opening and apart from said set, said last named means including means for securing said

antenna to said surface either parallel to said surface or at an angle thereto.

3. In a radio receiving set provided with an antenna carried by said set and operative under normal conditions to receive radio signals, the improvement which comprises means for enhancing reception of said signals under abnormal conditions when said set is positioned within a shielding structure having an opening therein, said means comprising an elongated flexible member electrically connecting said antenna to said set and vacuum cups carried by said antenna for quickly attachably and detachably securing the same to surfaces, including vertical surfaces, in any one of a plurality of positions relative to said opening and apart from said set, said vacuum cups being pivotally connected to said antenna to provide for securing said antenna to said surface either parallel to said surface or at an angle thereto.

4. A radio antenna comprising a rigid structure including conductors forming a loop, means carried by said structure for quickly attachably and detachably securing the same to a surface in any one of a plurality of positions on said surface and with said loop parallel to said surface or at an angle thereto.

5. A radio antenna comprising a panel member with antenna conductors supported thereby and forming a rigid structure with said member, and means carried by said member for quickly attachably and detachably securing the same to a surface in any one of a plurality of positions on said surface and either parallel to the surface or at an angle thereto.

6. A radio antenna comprising a panel member with antenna conductors supported thereby and forming a rigid structure with said member, and means carried by said member for quickly attachably and detachably securing the same to a surface in any one of a plurality of positions

on said surface and either parallel to the surface or at an angle thereto, said means comprising a plurality of vacuum cups pivotally connected to said member.

7. A radio antenna comprising a rigid structure including antenna conductors forming a loop antenna, and means carried by said structure for quickly attachably and detachably securing the same to a surface in any one of a plurality of positions on said surface and with said loop either parallel to the surface or at an angle thereto, said means comprising a plurality of vacuum cups hinged to an edge of said structure and another vacuum cup pivotally connected to a link which in turn is pivotally connected to said structure adjacent the center thereof.

8. A radio antenna comprising a rigid structure including antenna conductors forming a loop antenna, and means carried by said structure for quickly attachably and detachably securing the same to a surface in any one of a plurality of positions on said surface and with said loop either parallel to the surface or at an angle thereto, said means comprising an attaching member carrying a vacuum cup for attaching the same to said surface and a pivotal connection between said attaching member and said structure.

9. A radio antenna comprising a rigid structure including antenna conductors forming a loop, means carried by said structure for quickly attachably and detachably securing the same to a surface in any one of a plurality of positions on said surface and with said loop parallel to said surface or at an angle thereto, said means comprising an attaching member carrying a vacuum cup for attaching the same to said surface and a universal friction hinge connecting said attaching member and said structure.
